Specification for Design.

Patented Feb. 14, 1922.

Application filed May 19, 1921. Serial No. 470,900. Term of patent 14 years.

To all whom it may concern:

Be it known that I, GEORGE E. CURTISS, a citizen of the United States, residing at New Britain, county of Hartford, and State of Connecticut, have invented a new, original, and ornamental Design for Toasters, fully described and represented in the following specification and the accompanying drawings, forming a part of the same.

The drawing shows a perspective view of a toaster embodying the new design.

What is claimed is:

The ornamental design for a toaster, as shown.

In testimony whereof, I have hereunto set my hand.

GEORGE E. CURTISS.
